CLAIM

The ornamental design for a portable vaporizer for plant materials, as shown and described.

DESCRIPTION

FIG. 1 is a front perspective view of a vaporizer showing my new design.

FIG. 2 is a rear perspective view thereof.

FIG. 3 is a top plan view thereof.

FIG. 4 is a left side elevational view thereof, with the right side elevational view being a mirror image of FIG. 4.

FIG. 5 is a front elevational view thereof.

FIG. 6 is a bottom plan view thereof; and,

FIG. 7 is a rear elevational view thereof.
